UNITED STATES PATENT OFFICE.

JAMES K. DIAMOND, OF GRAND RAPIDS, MICHIGAN, ASSIGNOR TO J. B. STONE CO., OF GRAND RAPIDS, MICHIGAN, A CORPORATION OF MICHIGAN.

BELT-LACING MACHINE.

1,012,614.

Specification of Letters Patent. Patented Dec. 26, 1911.

Application filed March 8, 1911. Serial No. 612,009.

To all whom it may concern:

Be it known that I, JAMES K. DIAMOND, a citizen of the United States of America, residing at Grand Rapids, in the county of Kent and State of Michigan, have invented 5 certain new and useful Improvements in Belt-Lacing Machines; and I do hereby declare the following to be a full, clear, and exact description of the invention, such as 10 will enable others skilled in the art to which it appertains to make and use the same.

My invention relates to machines for lac- 15 ing belts and more particularly to machines for applying wire lacings of the form shown in the drawings, and its object is to provide the device with means for simultaneously clenching a series of the same, and to pro- 20 vide the device with various new and useful features hereinafter more fully described and particularly pointed out in the claims, 25 reference being had to the accompanying drawings in which:

Figure 1 is a side elevation of a device 30 embodying my invention; Fig. 2 a detail of the same in side elevation; Fig. 3 a side elevation showing the device as it appears 35 in operation; Fig. 4 a front elevation of the device in open position; Fig. 5 a detail in vertical section; Fig. 6 a detail in rear elevation; Fig. 7 an enlarged detail in vertical section from front to rear; and Fig. 8 a detail in plan view of the staple holding mechanism.

Like numbers refer to like parts in all of 35 the figures.

1 represents the frame or bed of the machine. 2 is a heavy pivot pin extending transversely therethrough near the middle of the same.

40 3 is an anvil to support the staples.

4 is a fixed staple holder at the rear of the anvil extending upwardly above the plane of the anvil and slotted at regular intervals to receive the loop end of the 45 staples. 5 is a removable pin extending through this holder to retain the staples therein.

6 is a movable gripping bar slotted at 50 intervals to intermesh with the holder 4, to engage the loops of the staples and force the same against the pin 5. This bar 6 is pivoted at 6^a to swing toward and away from the staples and is engaged at the rear by plungers 10 slidable in plugs 11 in the 55 end of spring chambers 9 in which chambers

are springs 9^a engaging the plungers and yieldingly forcing the same outward against the bar 6. These plungers are mounted in arms 8, one at each side of the machine, pivoted on the pin 2 and extending forwardly 60 above the anvil 3 to carry a clenching bar, preferably a square bar 7 adapted to engage the staples opposite the anvil 3 and clench the same into the end of the belt. Each end of the clenching bar 7 is provided with a 65 push pin 15 pivoted therein and having a limited swinging movement transversely of the bar. The upper end of this push pin is concave and engaged by a convex roller 14 mounted in a lever 13 pivoted near the roller 70 to apply pressure to the clenching bar 7.

26 are pins to engage the rollers when the same are substantially in line between the pivots of the levers 13 and the push pins 15 whereby a very great pressure is brought to 75 bear upon the bar 7. These levers 13 are carried in a metal frame 12 pivoted on the pin 2 and this frame is connected by a contractile spring 24 with the bar 7 whereby the push pins 15 are held in contact with the 80 rollers 14 and the bar 7 will rise toward the frame 12 as the levers are turned toward the vertical position. The spring 24 is inserted in an opening in the head of the frame 12 closed by a plug 25.

To follow up the action of the clenching bar step by step the rear of the frame 12 is provided with a pawl 16 which traverses a ratchet 17 pivoted at one end to the rear of the frame 1 and extending diagonally upward from the pivot toward the arm 12. To turn this ratchet out of the way to fully open the device for inserting the staples and to restore it again to place, the same is jointed as indicated and its operation illus- 90 trated in Figs. 1 and 2. To hold the end of the belt from slipping out of place, I provide a pivoted support 18 of inverted U-shape adapted to turn down out of the way, and supported in operative position as in 100 Fig. 3 by means of bolts 20 slidable in the frame and engaged with recesses in the support by springs 23. These bolts are pro- 95 vided with upwardly projecting pins by which they may be manipulated to release 105 the support. To retain the push pins 15 in place, I prefer to insert pivot pins 22 into the lower ends of the same, whereby they are pivotally retained in the sockets of the bar 7.

85

95

110

In operation, the device is first opened up as shown in Fig. 1, which gives free access to the holding means, and the staples or fasteners placed in the holder 4 and secured 5 therein by the pin 5. The device is then closed with the plungers 10 engaging the bar 6, thus forcing the staples firmly against the pin and holding the same in proper alignment. The clenching bar 7 is then brought 10 down upon the top of the staples and the pawl 16 engaged with the ratchet 17. By operating the levers 13, the clenching bar will be forced downward with sufficient power to clench or bend the staples, and by 15 reciprocating these levers, the bar will operate to clench the staples step by step, the pawl 16 taking up the slack at each stroke of the levers until the staples are firmly clenched within the end of the belt, this action 20 being best illustrated in Fig. 3. The springs 9^a maintain a constant and increasing pressure upon the bar 6 and insure proper alignment of the staples whereby they will bear uniformly on the coupling pin 25 when the belt is in use.

What I claim is:—

1. A machine for applying belt fasteners, comprising an anvil, means for holding a series of fasteners upon the anvil and spaced 30 apart, a clencher bar to engage the fasteners opposite the anvil, a pivoted arm movably supporting the bar, levers pivoted in the arm to force the bar against the fasteners, a pawl to hold the arm, and a ratchet engaged by 35 the pawl.
2. A machine for applying belt fasteners, comprising an anvil, a holder having vertical grooves at intervals, a removable pin extending through the grooves, a movable clamping 40 bar having projections to enter the grooves, springs to yieldingly force the bar toward the pin, a clencher bar above the anvil, and means for forcing said bar toward the anvil to 45 clenche the fasteners.
3. A machine for applying belt fasteners, comprising a frame or bed, an anvil supported on the bed, a holder at the rear of the anvil to adjust and hold fasteners upon the anvil, a vertically movable clenching bar 50 above the anvil, a pivoted arm carrying the clencher bar, levers pivoted in the arm to force the clencher bar toward the anvil, a

pivoted support near the front of the anvil, teeth in the support to engage and hold a belt with its end above the anvil, and spring 55 actuated bolts to hold and release the support.

4. A machine for applying belt fasteners, comprising a bed or frame, an anvil supported on the frame, a holder at one side of the anvil having slots at regular intervals to receive fasteners, a removable pin extending through the slots, a clamping bar having projections to enter the slots and engage the fasteners, arms pivoted to the frame, spring actuated plungers in the arms to engage the bar, a clencher bar carried by the arms and engaging the fasteners opposite the anvil, an arm above the clencher bar and pivoted to the frame, a pawl and ratchet 70 to hold said arm, levers pivoted in the arm to force the clencher bar downward, and a spring connecting the clencher bar and the arm to raise the clencher bar.

5. A machine for applying belt fasteners, 75 comprising an anvil, means for holding fasteners upon the anvil and spaced apart at regular intervals, a clencher bar above the anvil, pivoted arms supporting the bar, a pivoted arm between said arms, a spring 80 connecting said arm and the bar, levers pivoted in the middle arm, rollers journaled in the levers, and push pins mounted in the bar and engaged by the rollers.

6. A machine for applying belt fasteners, 85 comprising an anvil, a holder at one side of the anvil having vertical grooves at intervals, a removable pin extending through said grooves, a presser bar having projections within the grooves and movable toward and 90 away from said pin, pivoted arms provided with spring chambers, springs in the chambers, plungers projecting from the chambers and actuated by the springs to engage the bar, a clencher bar carried by the arms and 95 means for forcing the clencher bar toward the anvil to clench the fasteners.

In testimony whereof I affix my signature in presence of two witnesses.

JAMES K. DIAMOND.
